UNITED STATES PATENT OFFICE.

JOSEPH J. MAREK, OF VICTORIA, TEXAS.

BALING-PRESS.

1,094,734.

Specification of Letters Patent. Patented Apr. 28, 1914.

Application filed July 29, 1913. Serial No. 781,853.

To all whom it may concern:

Be it known that I, JOSEPH J. MAREK, citizen of the United States, residing at Victoria, in the county of Victoria and State 5 of Texas, have invented certain new and useful Improvements in Baling-Presses, of which the following is a specification.

This invention relates to baling presses, and has for its object the provision of a 10 simple and efficient press whereby cotton may be economically and expeditiously formed into a round bale.

A further object of the invention is to provide means whereby the compressing and 15 feeding belt or apron may be kept under the proper tension to feed and compress the cotton and also to provide means whereby the belt may be released from its tension after the bale has been formed to permit 20 the removal of the same from the press.

The invention also seeks, generally, to improve the construction of the parts of a cotton baling press whereby the efficiency and durability of the same will be increased 25 while the cost of production and maintenance will be kept within the bounds of economy.

The invention is illustrated in the accompanying drawings and will be hereinafter 30 first fully described and then more particularly pointed out in the claims following the description.

In the drawings: Figure 1 is a front elevation of a press embodying my improvements; Fig. 2 is a side elevation of the same; Fig. 3 is a plan view with the apron or belt arranged to permit the removal of the 35 formed bale; Fig. 4 is a vertical longitudinal section; Fig. 5 is a detail view of the 40 means for retaining the belt in its operative position.

In carrying out my invention, I employ a frame consisting of side plates or standards 1 connected by cross bars and plates 2 at 45 convenient points of the bottom, back and top, the top plate 2 having its front edge cut-away, as shown at 3, to facilitate the feeding of the cotton into the press and the removal of the bale therefrom. A guiding 50 chute 4 is fitted in the top plate 2 and this chute may be supplemental to or formed as a part of a large hopper, as will be readily understood. In each side plate or standard 1 at about the center thereof, I provide 55 bearings or journal boxes 5 which receive the trunnions or stub-shafts 6 formed on

disks 7 which are disposed adjacent the inner faces of the side plates and constitute the end compression members, the said disks being provided with annular flanges 60 8 which serve as guides to prevent the feeding and compressing belt or apron 9 from shifting laterally so as to wear against the sides of the frame. Above the disks 7 and in rear of the vertical plane of the axis 65 thereof, I provide a driving roller 10 which is journaled in suitable bearings in the side plates and is equipped at one end with a band pulley 11 through which power may be applied to the said roller from any convenient motor. At its opposite end, this driving roller is equipped with a gear wheel 12 which meshes with an idler 13 journaled upon a bracket 13' secured to the adjacent side plate and adapted to be engaged with 70 a gear wheel 14 on one end of a guiding roller 15 which is disposed above the disk 7 and in advance of the vertical plane of the axis thereof.

Below the disks 7 and at opposite sides of 75 the vertical plane of their axes, I provide idler rollers 16 and 17 which are journaled in suitable bearings 18 and 19 secured in the side plates of the main frame. The bearings 18 of the rear idler roller 16 are preferably 80 slidably mounted within a slot 20 formed in the adjacent side plate and defined by an external rib 21, as clearly shown in Fig. 2. Adjusting screws or bolts 22 are mounted in the end portions of this rib 21 so that the 85 bearings 18 may be adjusted forwardly or rearwardly so as to obtain the requisite tension upon the feeding and compressing belt or apron 9. As clearly shown in Fig. 4, the 90 said belt passes under the idler rollers 16 and 17 and over the driving roller 10 and the idler roller 15, the portion of the belt 95 between the rollers 10 and 15 passing downwardly around and under the disks 7. When the roller 15 is in its operative position, the 100 outlet from the chute or hopper will be directly between the said rollers so that the cotton passing through the same will drop into the main bight or turn of the belt 105 formed around the disks 7. As indicated by the arrows, the apron moves downwardly 110 across the open front side of the chute which is expressly formed with three sides so that the cotton will tend to rest upon the forward roller 15 and will be deflected from the rear roller 10. As a result of this arrangement, the movement of the belt will draw the cot-

ton downwardly into the sack formed by the main bight of the apron and will roll the cotton into a spiral which will eventually fill the space between the disks 7 and thereby tend to expand the innermost portion of the belt which is of stout canvas or other material capable of resisting this pressure and re-act upon the cotton so as to compress the same.

10 The roller 15 has its journals mounted in the upper ends of levers or carrying arms 23 which are pivoted at their lower ends to the side plates of the frame so that they may swing outwardly from the side plates or be swung inwardly so as to carry the journals of the roller 15 into notches or recesses 24 formed in the front edges of the side plates, as clearly shown. When the lever arms are in their lowered positions, they will 15 rest upon offsets or stops 25 rigidly secured to the side plates near the lower portions of their front edges. Rotatably fitted upon the journals of the roller 15 are latches 26 which have their inner ends provided with 20 down-turned hooks or teeth 27 adapted to engage behind catches or retainers 28 secured to the side plates of the frame preferably by the same bolts that secure the brackets 13' thereto. The said brackets will thereby 25 serve as keepers to prevent the latches 26 moving laterally out of engagement with the retainers 28 when the press is in operation.

It is thought the operation of my improved press will be readily understood from 30 the foregoing description, taken in connection with the accompanying drawings. When a bale is to be formed the latches 26 are pushed inwardly and upwardly so as to swing the lever arms 23 toward the central transverse plane of the press and thereby carry the upper ends of said arms to the inner ends of the notches or recesses 24. The 35 latches are then engaged over the retainers 28 and will hold the roller 15 in its upper operative position adjacent the mouth of the hopper or chute 4. When the roller 15 is thus moved to the inner end of the notches 24, the gear wheel 14 will be caused to mesh with the idler pinion 13, and, if the motor 40 be then started, the belt will be caused to travel in the direction indicated by the arrows in Fig. 4. The cotton will then be drawn into the space between the disks 7 and will be compressed into a round bale, 45 as hereinbefore set forth. After the bale has been formed the outer ends of the latches 26 are depressed, thereby releasing the hooks 27 from the retainers 28 and permitting the carrying arms 23 to be swung forwardly so that the roller 15 will be carried 50 to a position in front of the frame and the bale exposed so that it may be easily withdrawn. It will be understood, of course, before the apron is thus swung away from 55 the front side of the press, the bale ties or

cover cloth is fed into the main bight or turn of the apron and so run around the bale so that the bale ties may be fastened and the bale held against expansion. It will be readily noted that my press is exceedingly 70 simple in the construction and arrangement of its parts and may be very economically operated. Owing to the simplicity of its construction and the small number of parts employed, it is not liable to get out of order and repairs will be seldom needed. The 75 apron will readily accommodate itself to the shifting in the position of the roller 15 so that the removal of the formed bale may be accomplished in a very short space of 80 time, and the several rollers are formed with annular flanges 29 at their ends to prevent lateral movement of the apron and prevent 85 wearing of the edges thereof against the stationary plates of the frame.

What I claim is:—

1. A baling press comprising a main frame, a series of rollers mounted therein, disks journaled in the frame and forming end compression members, an endless apron carried by the several rollers and passing around the edges of the disks, and a guide disposed in the top of the frame and having its lower end arranged between the uppermost of said rollers.

2. A baling press comprising a main frame, a plurality of rollers mounted therein, disks mounted upon the sides of the frame and located between the rollers, an endless apron carried by the rollers and extending around the end disks, and a three-sided chute fitted in the top of the frame and having its lower end between the uppermost pair of rollers and its open side adjacent the forward roller of said pair of rollers.

3. A baling press comprising a main frame, a plurality of rollers mounted therein, disks mounted upon the inner sides of the frame, a belt trained around the said rollers and said disks, and means for moving one of the rollers to and from the disks.

4. A baling press comprising a main frame, a plurality of rollers mounted therein, disks mounted upon the inner sides of the frame, a belt trained around the said rollers and said disks, means for moving one of the rollers to and from the disks, and means for holding the said roller in its inner position.

5. A baling press comprising a pair of standards having inwardly extending notches in their front edges at their upper ends, a plurality of rollers journaled in and extending between the said standards, a roller adapted to fit in the said notches, disks journaled upon the standards and disposed adjacent the inner faces thereof, a belt trained around the several rollers and said disks, and means for retaining the movable roller at the inner ends of the said notches.

6. A baling press comprising a pair of

standards, a plate secured to and extending between the upper ends of said standards and having its front edge cut-away, a chute fitted in said plate in rear of and communicating with said cut-away portion, a plurality of rollers extending between the standards, one of said rollers being disposed immediately adjacent the rear of the said chute and another of said rollers being normally adjacent the front of said chute, disks below the said two rollers, an apron trained around the several rollers and the said disks, and means for shifting the forward roller to and from the chute.

7. The combination of a main frame, a plurality of rollers journaled therein, end disks supported by the frame between the said rollers, carrying arms pivoted at their lower ends to the main frame, a roller carried by the upper ends of said arms, a belt trained around the said roller, disks and the first-mentioned rollers, and means for locking the carrying arms in operative position.

8. The combination of a main frame, re-

tainers secured upon the sides thereof at the upper end of the same, rollers fitted within the main frame, disks fitted in the frame between the said rollers, carrying arms pivoted upon the frame, a roller journaled in the upper ends of said carrying arms, an apron trained around the said roller, the said end disks and the first-mentioned rollers, and latches mounted upon the said last-mentioned roller and adapted to engage the said retainers.

9. A baling press comprising a supporting frame, rotary end compression disks mounted upon the inner sides of the frame, a plurality of rollers disposed within the frame around said disks, a belt trained around the several rollers and the disks, and means for rotating the several rollers.

In testimony whereof I affix my signature in presence of two witnesses.
